(57) **CLAIM**

The ornamental design for a lid for a medical implant, as shown and described.

DESCRIPTION

Lid for a medical implant

1.1 is a front view of the invention in a closed position;
1.2 is a rear view of the invention in a closed position;
1.3 is a side view of the invention in a closed position;
1.4 is a bottom view of the invention in a closed position;
1.5 is a top perspective view of the invention in a closed position;
1.6 is a side view of the invention in a closed position;
1.7 is a top view of the invention in a closed position;
1.8 is a front view of the invention in an open position;
1.9 is a rear view of the invention in a closed position;
1.10 is a side view of the invention in a closed position;
1.11 is a bottom view of the invention in a closed position;
1.12 is a top perspective view of the invention in a closed position;
1.13 is a side view of the invention in a closed position; and
1.14 is a top view of the invention in a closed position.
